DESIGN FOR AN ANTISKID CHAIN LINK

Conrad H. Sloan, Duluth, Minn.

Application November 8, 1946, Serial No. 134,615

Term of patent 14 years

(Cl. D90—20)

To all whom it may concern:

Be it known that I, Conrad H. Sloan, a citizen of the United States, residing at Duluth, in the county of St. Louis and State of Minnesota, have invented a new, original, and ornamental Design for an Anti-Skid Chain Link, of which the following is a specification, reference being had to the accompanying drawing, forming part thereof.

In the drawing:

Fig. 1 is a traction face view of an anti-skid chain link showing my new design;

Fig. 2 is a side elevational view of Fig. 1.

Fig. 3 is an end elevational view of Fig. 1.

I claim:

The ornamental design for an anti-skid chain link, as shown.

CONRAD H. SLOAN.
